TOY PISTOL

Percy H. Milbery, Pembroke, Mass., assignor to
National Fireworks, Inc., West Hanover, Mass.,
a corporation of Massachusetts

Application April 18, 1933, Serial No. 666,665

8 Claims. (Cl. 42—57)

This invention relates to improvements in toy pistols, and the principal object thereof is to provide an improved mechanism for insuring more accurate firing of the explosive pellets of strip ammunition.

In repeating toy pistols heretofore constructed the means for feeding the ammunition strip to position the pellets successively upon the anvil comprises a spring or other device adapted to engage the tape rearwardly of and in proximity to the terminal unexploded pellet and upon reTRACTING or COCKING movement of the hammer to advance the tape sufficiently to position the terminal pellet upon the anvil, and upon release 10 of the hammer to ride backwardly over the tape and the next succeeding pellet and engage the tape again in proximity to the next succeeding pellet before the hammer strikes the positioned pellet. In all such constructions the pellet next 15 succeeding the positioned pellet is exposed at the time the hammer strikes and explodes the positioned pellet. The back fire from the exploding pellet therefore may and often does ignite the next succeeding pellet so that the pistol will 20 misfire upon the next actuation of the hammer.

In some of the prior constructions such backfire has ignited other pellets causing an explosion of the remainder of the pellets of the tape and injuring the hand of the operator.

One of the objects of the present invention 30 is to provide protective means for preventing back-fire from the exploding pellet into the next succeeding pellet, or to any other pellet of the ammunition strip.

A further feature of the invention consists in providing the hammer with a flat spring which 35 will engage the strip of tape between the positioned pellet and the next succeeding pellet before the hammer strikes the positioned pellet, and which preferably acts during the initial 40 movement of the hammer to supplement the feeding of the tape and upon further retraction of the hammer is removed from engagement with the tape in such manner as to remove and tear away fragments of the tape which may have 45 become deposited upon the anvil during the explosion of a preceding pellet.

A further object of the invention is to provide 50 a pistol of the character above described with novel means for retracting the hammer which will be positive in its action both in retracting the hammer and certain in releasing the hammer when it has been retracted to a predetermined distance, thereby preventing any possible 55 premature explosion of the pellet.

These and other objects and features of the invention will more fully appear from the following description and the accompanying drawing and will be particularly pointed out in the claims.

In the drawing:

Fig. 1 is a side elevation of a toy pistol embodying the invention, portions of one side of the casing having been removed to illustrate the mechanism and showing the hammer in normal position in engagement with the anvil, and the 60 protecting member between the terminal unexploded pellet and the anvil;

Fig. 2 is a similar view illustrating the hammer in retracted or cocked position just before it is released to strike the positioned explosive 65 pellet; and,

Fig. 3 is a perspective view of the preferred 70 form of hammer showing the manner in which a combined feeding spring and protector spring is mounted upon the hammer.

The toy pistol illustrated in the accompanying 75 drawing comprises a casing 1 in the form and general appearance of a pistol preferably of the automatic type. The casing preferably is made of cast metal formed in two complementary 80 sections, one of which is not shown, which when fastened together by a suitable bolt or rivet 2 form a hollow chamber in which the working mechanism of the pistol is located. The back 3 of the casing is made separate from the side members thereof and is pivotally secured thereto by bosses 4 extending into suitable sockets in the walls of the side members of the casing. The upper end of the back member is provided with a front flat face 5 forming an anvil with which 85 the hammer co-operates. One side of the lower portion of the back member is provided with a flat lateral extension or flange 6 forming a part of the handle member of the pistol.

The hollow handle portion of the pistol 90 comprises a chamber 7 to receive a strip, preferably a roll, of tape ammunition and is provided with a stud 8 extending from the wall of the casing upon which the roll of tape may be mounted.

The hammer member 9 is of general rectangular 100 shape and provided with a central recess to reduce its weight, and has an upward extension forming a hammer 10 presenting a flat face adapted to engage the anvil 5. The hammer is normally held in contact with the anvil by a 105 spring, preferably in the form of a resilient wire 11, which is coiled about one of two axially aligned studs 12 which project from opposite sides of the hammer in axial alinement and are journaled in the sides of the casing and form the pivot of the 110

hammer. One end of the spring 11 rests upon a shoulder 13 of a boss integral with and forming part of one member of the casing, while the other end portion of the spring extends through the 5 aperture in the hammer and engages the shoulder of a web 14 which partially closes the aperture in the hammer.

The hammer is provided with an extension 15 which extends upwardly in substantial parallelism with the hammer and to a considerable 10 distance from the pivot of the hammer to provide such leverage as will enable the hammer to be easily retracted or cocked. The extension 15 is provided with a preferably curved shoulder 16 15 adapted to be engaged by a trigger mechanism for retracting the hammer. The trigger mechanism comprises a lever 17 which is provided with pivotal studs 18 extending in axial alignment from opposite sides of the trigger lever and 20 are journaled in the walls of the casing. The trigger lever has a curved lower end portion 19 projecting below the casing to be engaged by the finger, and an upwardly extending arm 20 to which is pivoted a link member 21 having a loop 25 or slot to engage the shoulder 16 of the projection 15 upon the hammer.

Desirably the link 21 is formed of sheet metal bent to inverted U-shape in cross section and provided with a central slot 22 to receive the extension 15 of the hammer and to engage the shoulder 16 thereof. The central portion of the U-shaped member is provided with a forward extension 23 which is bent downwardly and has a perforation 24 to receive the end of a spring 25 30 preferably in the form of a wire which is coiled about the stud 18, and the opposite end of which engages a suitable abutment 26 upon the casing. The action of the spring tends to force the free end of the link into engagement with the hammer, as illustrated in Fig. 1, so that the projection 15 of the hammer extends through the slot 22 when the hammer is in normal position in engagement with the anvil, as illustrated in Fig. 1. The action of the spring also advances 35 the finger end 19 of the trigger into the position from which it may be pulled by the finger to retract the hammer.

In the operation of the device the pulling of the trigger draws the link 21 forwardly so that its engagement with the shoulder 16 of the projection 15 of the hammer retracts the hammer until the shouldered portion 16 of the hammer assumes such position that it will ride out of the slot, as illustrated in Fig. 2, thereby releasing the hammer and permitting it to be forced by the action 5 of the hammer spring 11 into engagement with the anvil.

By reason of this construction a powerful leverage is exerted by the trigger upon the hammer 0 which enables it to be retracted easily and to such distance as to insure a sufficient stroke of the hammer upon the anvil unfailingly to explode the pellet which is positioned upon the anvil.

One of the principal objects of the present invention is to provide means for insuring the positive feeding movement of the pellet of the tape to the anvil and to provide a protecting device which will engage the tape in proximity to the 0 anvil and prevent back-fire of the exploding pellet into any other pellet of the tape. In previous toy pistol constructions the explosive pellet next to the pellet which is positioned upon the anvil at the time the hammer strikes it, has not been 5 protected from such back-fire. The present in-

vention comprises a protective device which engages the tape between the positioned pellet and the next pellet before the hammer strikes the positioned tape. Any such protective device may be employed. In the preferred embodiment of the invention illustrated herein the protective device is mounted upon the hammer and so positioned that when the hammer has been released the protective device will engage the tape sufficiently in advance of the impact of the hammer upon the positioned pellet to prevent the back-fire of the exploding pellet from igniting the next pellet of the tape, or any other pellet thereof.

The protective device may be secured to the hammer in any suitable manner to co-operate with the usual type of feeding spring which is carried by the hammer in toy pistols of this type. In the preferred construction illustrated herein a single flat spring, carried by the hammer, serves both as a feeding spring and a protective device of the character above described. In this construction the lower portion of the hammer is provided with a circular socket 27 which receives the looped portion 28 of a flat spring, one member 29 of which extends rearwardly and upwardly to engage the tape and constitutes a feeding spring, while the other member 30 of which engages the tape in advance of the end of the feeding spring in such manner as to supplement the action of the feeding spring during the initial advancing movement of the tape which is produced by the retraction of the hammer, the protective device being withdrawn from engagement with the tape upon further retracting movement of the hammer and acting when so removed to displace any fragments of the tape which may have adhered to the hammer, or which may lie in the path of the hammer and thereby cushion the action of the hammer upon the positioned pellet.

In the construction illustrated the tape 31, which preferably is in the form of a roll 32, is placed upon the stud 8 of the casing and is led upwardly along the inner wall of the back 3 to the anvil beneath the free end of a flat detent spring 33, the opposite end of which is secured in a recess 34 in a boss 35 projecting from the casing 1. The spring is held under tension by a lug 36 also projecting from the wall of the casing. The feeding member 29 of the spring, 120 which is carried by the hammer, engages the tape just beyond the end of the detent spring when the hammer is in normal position in engagement with the anvil and engages the tape just behind the pellet which is to be positioned upon the anvil. The protective member 30 of the spring engages the tape in front of the pellet to be next positioned upon the anvil, as illustrated in Fig. 1.

Upon the pulling of the trigger the hammer is 135 retracted, as illustrated in Fig. 2, and the movement of the hammer about its pivot causes the feeding and protective detent springs 29 and 30 to advance the tape toward the anvil. In the initial feeding movement both the springs 29 and 30 act conjointly to feed the tape, thus insuring a positive movement of the tape. As the hammer is retracted further the protective spring 30 is withdrawn from engagement with the tape and by its removal serves to dislodge any pieces 140 of the tape which may have adhered to the anvil, or which may extend above the line of engagement of the protective spring therewith, thereby cleaning the anvil of debris before the pellet is to be exploded as positioned upon the 150

- anvil. The refractive movement of the hammer is such that the feeding spring advances the pellet to be exploded until it rests in proper position upon the anvil. When the trigger has been drawn sufficiently to cause the link 21 to release the hammer, as illustrated in Fig. 2, the hammer is impelled by its spring 13 against the tape. During the striking movement of the hammer the feeding spring 29 rides backwardly over the tape to engage rearwardly of the next pellet which is to be positioned upon the anvil. During such striking movement the protective spring engages the tape in front of the next pellet before the hammer strikes and explodes the positioned pellet, so that neither the next pellet to be positioned nor any of the other pellets can be ignited by back-fire.
- Any suitable means may be provided for securing the combined feeding and protective springs in the circular recess in the hammer. Desirably this is accomplished by providing a cylindrical stud 37 upon the hammer which extends through a complementary aperture in the protective portion 30 of the spring. This construction is of great advantage for the reason that in previous constructions it has been necessary to bend the lower end of the feeding spring abruptly and seat it in an angular recess in the hammer, whereas by the present construction the socket in the hammer can be made to conform to the natural cylindrical curvature which results from bending the spring into U-shape, and the engagement of the spring with the stud is readily accomplished, without requiring special tools for bending the end of the feeding spring as were employed in previous constructions.
- By virtue of the present invention therefore a more positive feeding movement of the tape is acquired, full protection is provided against back-firing, and more positive and certain actuation of the hammer is attained.
- While the invention is illustrated and described herein as applied to a toy pistol construction in which the anvil is located at the upper end of the pivotally mounted back member of the casing, and the hammer so disposed as to co-operate with the anvil, it will be understood that the invention may be embodied in other forms of toy pistols, such, for example, as those in which the anvil is located in the horizontal position within the upper portion of the casing or adjacent to the muzzle of the pistol, and that various changes in form, construction and arrangement of parts may be made within the spirit and scope of the following claims.
- Having thus described the invention, what is claimed as new, and desired to be secured by Letters Patent, is:
1. A toy pistol comprising a casing having a magazine to support a strip of tape ammunition, an anvil, means for guiding the tape to said anvil including a detent for preventing retrograde movement of the tape, a spring-actuated hammer in co-operative relation to said anvil, means for retracting the hammer against the action of the spring, a tape-feeding spring operable by the retracting movement of the hammer to advance the tape and position an explosive pellet thereof upon the anvil, a protector and means for causing the same to engage the tape between the feeding spring and the anvil and rearwardly of and in proximity to the positioned pellet before the released hammer strikes the pellet, thereby prevent back-firing of the exploding pellet into another pellet of the tape.
2. A toy pistol comprising a casing having a magazine to support a strip of tape ammunition, an anvil, means for guiding the tape to said anvil including a detent for preventing retrograde movement of the tape, a spring-actuated hammer in co-operative relation to said anvil, means for retracting the hammer against the action of the spring, a tape-feeding spring on said hammer operable by the retracting movement of the hammer to position an explosive pellet of the tape upon the anvil, and a protector movable by said hammer, during its striking movement, into engagement with the tape between the feeding spring and the anvil and in proximity to the positioned pellet before the released hammer strikes the pellet, thereby preventing back-firing of the exploding pellet into another pellet of the tape.
3. A toy pistol comprising a casing having a magazine to support a strip of tape ammunition, an anvil, means for guiding the tape to said anvil including a detent for preventing retrograde movement of the tape, a spring-actuated hammer in co-operative relation to said anvil, means for retracting the hammer against the action of the spring, means including a tape-feeding spring portion on said hammer operable by the retracting movements of the hammer to position the explosive pellets of said tape successively upon the anvil, and a protector spring portion on said hammer movable by the striking movement of said hammer into engagement with the tape in proximity to the anvil before the hammer strikes the pellet which is positioned upon the anvil.
4. A toy pistol comprising a casing having a magazine to support a strip of tape ammunition, an anvil, means for guiding the tape to said anvil including a detent for preventing retrograde movement of the tape, a spring-actuated hammer in co-operative relation to said anvil, means for retracting the hammer against the action of the spring, a U-shaped flat spring having arms adapted to contact the tape and its looped portion seated in a complementary recess in the hammer so positioned that one arm of said U-shaped spring will be maintained in engagement with the tape and will act upon retracting movement of the hammer to advance the tape and position a pellet upon the anvil, and the other arm of said spring will be removed from the tape during the retracting movement of the hammer and upon release of the hammer will engage the tape in proximity to the anvil before the hammer strikes the explosive pellet, thereby preventing ignition of any other pellet by back-fire.
5. A toy pistol comprising a casing having a magazine to support a strip of tape ammunition, an anvil, means for guiding the strip of ammunition to said anvil including a detent for preventing retrograde movement of said tape, a pivotally mounted spring-actuated hammer having a circular socket therein, a U-shaped flat spring seated in said socket, presenting a feeding member engaging the tape rearwardly of the terminal pellet, and a protector member of shorter length to engage the tape in front of the terminal pellet when the hammer is in normal position engaging the anvil and movable by the retracting movement of the hammer first longitudinally in co-operation with the feeding member to advance the tape and thereafter away from the tape, thereby removing from the anvil any fragments of tape which may have adhered to it, and movable upon release of the ham-

mer into engagement with the tape before the hammer strikes the pellet.

6. A toy pistol comprising a casing having a magazine to support a strip of tape ammunition, an anvil, means for guiding the strip of ammunition to said anvil including a detent for preventing retrograde movement of said tape, a pivotally mounted spring-actuated hammer having a circular socket therein, a U-shaped flat spring seated in said socket, and locked therein by a stud extending from the wall of said socket through an aperture in said spring, said spring presenting a feeding member engaging the tape rearwardly of the terminal pellet, and a protector member engaging the strip in front of said pellet when the hammer is in normal position engaging the anvil, whereby upon retraction of said hammer the feeding member will advance the tape to position the terminal pellet thereof upon the anvil and upon release of the hammer the protector member will engage the tape intermediate of the positioned pellet and the next succeeding pellet of the tape before the hammer strikes the positioned pellet.

25. 7. A toy pistol comprising a casing having a magazine to support a strip of tape ammunition, an anvil, means for guiding the tape to said anvil including a detent for preventing retrograde movement of the tape, a pivotally mounted spring-actuated hammer in co-operative relation to said anvil having a shouldered portion extending in substantial parallelism with the hammer, a trigger pivotally mounted in said casing in front of said hammer, a link pivotally mounted on an extension of said trigger having means detach-

ably engaging said shouldered projection operable upon the pulling of said trigger to retract the hammer until it is swung into such position as to disengage said shoulder from said link and thereby release the hammer, means for causing re-engagement of said link with said shouldered projection upon release of the trigger, and feeding means operable by the retracting movement of the hammer to advance the tape and position the terminal pellet thereof on the anvil before the release of said hammer.

8. A toy pistol comprising a casing having a magazine to support a strip of tape ammunition, an anvil, means for guiding the tape to said anvil including a detent for preventing retrograde movement of the tape, a pivotally mounted spring-actuated hammer in co-operative relation to said anvil having a shouldered portion extending in substantial parallelism with the hammer, a trigger pivotally mounted in said casing in front of said hammer, a U-shaped sheet metal link pivotally mounted on an extension of said trigger and having a slot engaging said shouldered projection operable upon the pulling of said trigger to retract the hammer until it is swung to such position as to withdraw said shoulder from said slot, and a spring mounted on said casing engaging said link and acting to cause re-engagement of said slot with said shouldered projection upon release of the trigger, and a spring on said hammer operable by the retracting movement thereof to advance the tape and position the terminal pellet thereof upon said anvil.
